FUEL FEED APPARATUS FOR INTERNAL
COMBUSTION ENGINES

Nicolas Leisten and Charles Senn, Detroit, Mich.

Application February 11, 1932, Serial No. 592,277

15 Claims. (Cl. 261—18)

This invention relates to fuel feed apparatus for internal combustion engines.

An object of the invention is to provide a carburetor eliminating the usual throttle and making an improved provision for thoroughly atomizing liquid fuel.

Another object is to provide for alternative delivery of liquid fuel or gas to an internal combustion engine.

Another object is to provide improved hydraulic means for controlling such alternative delivery.

A further object is to thermostatically control the delivery of liquid fuel to a gas generator, and thus insure a gas generating temperature when delivery is established.

These and various other objects the invention attains by the construction hereinafter described, and illustrated in the accompanying drawings, wherein:

Fig. 1 is a view in side elevation of a vehicle motor diagrammatically showing the herein-disclosed provision for fueling said motor, a fragmentary, sectional showing of the vehicle foot board being further included.

Fig. 2 is an axial, vertical, sectional view of the carburetor of said motor, taken upon the line 2—2 of Fig. 1.

Fig. 3 is a sectional detail taken upon the line 3—3 of Fig. 1 and showing one of several duplicate fluid pressure responsive devices for actuating fuel valves of said carburetor.

Fig. 4 is a cross sectional view of a compressed air heating chamber carried by the exhaust manifold of said motor, taken upon the line 4—4 of Fig. 1.

Fig. 5 is a horizontal, sectional view taken upon the line 5—5 of Fig. 1, and showing a gas generator installed in a second heating chamber carried by the exhaust manifold.

Fig. 6 is a vertical, sectional view of the same taken upon the line 6—6 of Fig. 5.

Fig. 7 is a vertical, sectional view of a gas pressure regulator, taken upon the line 7—7 of Fig. 1.

In these views, the reference character 1 designates an internal combustion engine having intake and exhaust manifolds designated 2 and 3 respectively.

A carburetor 4 attached to the manifold 2, therebeneath, comprises a mixing chamber 5 having an outlet to said manifold. The primary air supply to said mixing chamber is established through a plurality of openings 6 formed in a cup-shaped head 7 attached to the lower end

of the carburetor, and centrally formed in said head is an orifice 8 for delivery to the mixing chamber of a gaseous fuel. Said orifice is controlled by a needle valve 9 comprising a stem mounted for vertical travel axially of the mixing chamber in a pair of spaced plates 10 and 11, apertured for the passage of air and fuel. A spring 12 coiled upon the stem of the valve 9 urges the latter upwardly to uncover the orifice 8, and a cam 13 bearing upon the upper end of said stem is adapted to selectively lower said stem to regulaely close said orifice. Said cam is fast on a shaft 14 extending exteriorly of the carburetor and carrying on its outer end an actuating arm 15.

The valve stem 9 further carries a disk valve member 16 controlling the admission of primary air to the mixing chamber, said member seating on the peripheral wall of the head 7, and said wall being flared for that purpose.

Gaseous fuel is adapted to be delivered to the orifice 8 from a gas storage tank 17 by way of a pipe 18, and under control of a valve 19. Said tank is supplied with gaseous fuel through a pipe 20 leading from a gas generator carried by the exhaust manifold.

This generator (as best appears in Figs. 5 and 6) comprises a heating chamber 21 mounted on and opening into the exhaust manifold and having a tubular vaporizing pipe 22 extending from end to end thereof and connected at one end to the pipe 20. Liquid fuel is delivered to the other end of the pipe 22, after flowing through a preheating tube 23 which extends through the casing 21 from end to end thereof, and is bent exteriorly of said casing to enter the vaporizing pipe and has within the latter a plurality of small outlets 24. The pipe 22 is filled with finely divided metal 25, as for example steel wool, to promote the heating and consequent vaporization of liquid fuel.

Liquid fuel is delivered to the inlet end of the preheating tube 23 through a pipe 26 to which it is delivered by any suitable pump 27 having its intake connected through a pipe 28 and suitable branches to two liquid fuel reservoirs 28a and 28b for respectively storing high test and low test liquid fuel. Valves 28c permit selective connection of these reservoirs to the pump. A chamber 29 for trapping gas or air is preferably connected to said pipe at some intermediate point thereof.

Branching from the pipe 26 is a pipe 30 leading to a fuel atomizer comprising a casing 31 having an air inlet 32 and a flaring outlet 33.

opening into the mixing chamber 5. A needle valve 34 reciprocatory in the casing 31 controls liquid fuel delivery to said outlet, and is downwardly urged toward an open position by a spring 35. For closing said valve, its lower end is engaged by a cam member 36 fast on a shaft 37 carrying a control arm 38.

Air is delivered to the inlet 32 from a compressor 39, which, as illustrated, is united with the pump 27. Such delivery is effected through a line comprising pipe sections 40 and 40a between which is interposed an air heating tube 41 positioned in a heating chamber 42 carried by and communicating with the exhaust manifold 3. Thus the secondary air stream delivered to the mixing chamber at 33 is preheated to a predetermined temperature.

Preferably the air heating tube 41 has an inlet 43 thereto for atmospheric air, established through a small fitting 43a extended through the side wall of the heating chamber 42 (see Fig. 4), said inlet being normally closed by a check valve 43b urged to its seat by a light spring. If for any reason, the air compressor ceases to function, a vacuum tendency will be transmitted to the heater tube 41 from the mixing chamber 5 through the pipe section 40a, whereby atmospheric pressure will unseat said check valve, admitting atmospheric air to the heating tube to maintain the secondary air supply to the mixing chamber.

The valve 19 is angularly operable by an arm 44. Said arm and each of the arms 15 and 38 are individually engaged by links 45 for actuating said arms from plungers 46 reciprocatory in cylinders 47, 47a, and 47b (see Fig. 3). Within the latter, coiled springs 48 urge said plungers to intermediate positions tending to effect seating of the valve members 9, 34, and 19. For unseating said valve members, fluid pressure is applicable to the plungers 46 within the cylinders 47 to overcome the springs 48. Thus, said cylinders are individually connected by pipes 49, 49a and 49b, to a primary control cylinder 50 mounted beneath the foot board 51 of the motor vehicle and having a piston 52 reciprocatory therein to displace a pressure-transmitting liquid through said pipes. Said piston is operable by a foot pedal 53 positioned above said floor board and connected to the piston through a suitable stem. The pipes 49a and 49b are individually controlled by valves 54a and 54b operable from the driver's seat (not shown).

It is preferred to insert in the pipe 18 a pressure regulating device, such as exemplified in Fig. 7, which will permit gas from the tank 17 to flow to the mixing chamber at a definite predetermined pressure regardless of variations of pressure in said tank.

Said device may comprise a casing 55 having a port 56 therein controlled by a disk valve member 57 carried by a diaphragm 58. Said valve member is urged to its seat by a spring 59 under pressure regulable by an adjustable plug 60. A smaller valve member 61 is urged by a spring 62 against the intake side of the port-forming member, being restrained by a pin 63 on the valve member 57 so that it may approach its seat only in proportion to withdrawal of the valve member 57 from its seat. Thus the flow of gas through the port 56 is limited to maintain the gas under a predetermined pressure after passing through said port.

Preferably liquid fuel delivery to the preheat-

ing tube 23 is automatically regulated by a thermostatic valve 64, the stem of which may carry an arm 65 connected to one end of a rod 66 passing longitudinally through the heating chamber 21 and fixed at its other end. Said rod is formed of a material (preferably metallic) having a high coefficient of expansion.

Until the temperature of the heating chamber 21 (and consequently of the rod 66) reaches a predetermined magnitude, the valve 64 remains closed or substantially so. When, however, a gas-generating temperature is reached, expansion of the rod 66 becomes such as to open said valve, and thereby establish a free flow of liquid fuel to the preheating and gas-generating tubes.

In use of the described apparatus, the engine is normally operated on dry gas delivered from the tank 17, the valves 9, 19 and 16 being regulably unseated to admit such gas in a desired volume to the mixing chamber, together with a proportionate volume of primary air. During such normal operation, the valve member 34 is seated, cutting off delivery of liquid fuel to the mixing chamber. To avoid unseating of the last-named valve member responsive to manipulation of the piston 52 by the foot pedal 53 it is necessary during normal operation that the valve 54a be closed, preventing transmission of fluid pressure through the pipe 49a. In operating the engine on dry gas, as described, the fuel delivered to the gas-generating chamber may be kerosene or a low grade of gasoline or the like.

To establish an initial supply of gas in the tank 17, it will, of course, be necessary to operate the engine for at least several minutes on liquid fuel. Liquid fuel operation may be established at any other desired time, and particularly when it is preferred, for any reason, to employ a good grade of gasoline rather than cheaper inferior grades, or kerosene.

In operating on liquid fuel, the valve 19 is held closed by the spring 48 in the cylinder 47b, the plunger in said cylinder being rendered unresponsive to the foot pedal 53 by maintaining the valve 54b closed.

During liquid fuel operation, the fuel is delivered to the mixing chamber in highly atomized form, due to the Venturi shape of the air passage within the chamber 31 and the velocity of the air passing through said passage. Furthermore, a high degree of turbulency results from delivery of the rich mixture of secondary air and fuel into the primary air stream, transversely to the flow of the latter, whereby a still finer subdivision of the fuel is effected. Pre-heating of the secondary air further tends towards thorough vaporization of the fuel, and also raises the temperature of the mixture as delivered to the engine to the point of maximum efficiency.

In operating on gas, the secondary air stream continues to exercise a mixture-heating function and cooperates further with the primary air to establish proper proportions for the gaseous mixture.

While it is apparent that the illustrated embodiment of our invention is well calculated to adequately fulfill the objects and advantages primarily stated, it is to be understood that the invention is susceptible to variation, modification and change within the spirit and scope of the subjoined claims.

What we claim is:

1. A carburetor comprising a mixing chamber having a primary air inlet, means for delivering secondary air to said mixing chamber under compression, means for mixing liquid fuel with the secondary air prior to its discharge into the mixing chamber, and means for delivering gaseous fuel to the mixing chamber.
2. A carburetor comprising a mixing chamber, a head closing an end of said chamber having a primary air inlet and having a flared annular wall, and formed with a gaseous fuel inlet, a disk valve member seating on said annular wall within said head to control a flow of primary air to the mixing chamber, a valve member controlling the gaseous fuel inlet, and means for operating said valve members in common.
3. In a fuel feed apparatus for internal combustion engines, the combination with the exhaust manifold and carburetor thereof, of a gas generator subject to exhaust manifold heat, means for delivering liquid fuel to said generator, means for delivering vaporized fuel from said generator to the carburetor, an air heater carried by said manifold, means for delivering compressed air through said air heater to the carburetor, and means for supplying liquid fuel to the compressed air stream.
4. In a fuel feed apparatus for internal combustion engines, the combination with an engine carburetor, of a gas generator, means for delivering liquid fuel to said generator, means for delivering vaporized fuel from the generator to the carburetor, means for delivering compressed air to the carburetor, means for supplying liquid fuel to the compressed air stream, and means for applying the exhaust gas heat of said engine to both the generator and said compressed air delivery means.
5. In a fuel feed apparatus, the combination with a carburetor, means for supplying gaseous fuel to the carburetor, means for supplying liquid fuel to the carburetor, valves separately controlling the delivery of said fuels to the carburetor, fluid pressure motors for operating said valves, an actuating element for said motors, and means for rendering said motors selectively responsive to said element.
6. A carburetor comprising a mixing chamber, a stem reciprocatory in said chamber, valves carried by said stem individually controlling air and fuel delivery to said chamber, a spring acting on said stem, urging said valves correspondingly from their seats, a cam member terminally engaging said stem for seating said valves, and means exteriorly carried by the carburetor for actuating said cam member.
7. In a fuel feed apparatus for internal combustion engines, the combination with a carburetor having a mixing chamber, means for regulably supplying a gaseous fuel to said mixing chamber, means for regulably supplying a liquid fuel to said mixing chamber, means for regulably admitting air to said mixing chamber, and a common control mechanism for all of said means, selective as regards control of said gaseous fuel supply means and liquid fuel supply means.
8. In a fuel feed apparatus for internal combustion engines, the combination with a carburetor having a mixing chamber, of means for regulably supplying gaseous fuel to said chamber, means for regulably supplying liquid fuel to said chamber, means for regulably admitting air to said chamber, fluid motors for individually effecting regulation of said means, and mechanism for applying fluid pressure selectively to said motors.
9. In a fuel feed apparatus for internal combustion engines, the combination with a carburetor having a mixing chamber and an air inlet to said chamber, of means for regulably supplying gaseous fuel to said chamber, means for regulably supplying liquid fuel to said chamber, fluid motors for individually effecting regulation of said means, and mechanism for applying fluid pressure selectively to said motors.
10. In a fuel feed apparatus for internal combustion engines, the combination with a carburetor having a mixing chamber and an air inlet to said chamber, of means for regulably supplying gaseous fuel to said chamber, means for regulably supplying liquid fuel to said chamber, means for regulably admitting air to said chamber, motors for individually effecting regulation of said means, and mechanism for remotely controlling said motors, selectively effective on the motors regulating gaseous fuel delivery and liquid fuel delivery.
11. In a fuel feed apparatus for internal combustion engines, the combination with a carburetor having a mixing chamber and an air inlet to said chamber, of means for regulably supplying liquid fuel to said chamber, means for regulably supplying gaseous fuel to said chamber, motors for individually effecting regulation of said means, and mechanism establishing a remote control of said motors, selectively.
12. In a fuel feed apparatus for internal combustion engines, the combination with a carburetor having a mixing chamber and an air inlet to said chamber, of a gas storage tank, a delivery connection from said tank to said chamber, a valve controlling said delivery connection, a valve controlling said air inlet, and means establishing a remote control of said valves, in common.
13. In a fuel feed apparatus for internal combustion engines, the combination with a carburetor having a mixing chamber and an air inlet to said chamber, of a gas storage tank, a delivery connection from said tank to said chamber, a valve controlling said delivery connection, a valve controlling said air inlet, fluid motors for individually operating said valves, and a common means for applying fluid pressure to said motors.
14. In a fuel feed apparatus for internal combustion engines, an air heater, means for delivering compressed air to the heater and from the heater to an engine intake, said heater having an inlet for atmospheric air, and a closure for said inlet biased to a normally closed position and adapted to open responsive to a reduction of pressure in the heater below atmospheric pressure.
15. In a fuel feed apparatus for internal combustion engines, the combination with a carburetor, of means for regulably supplying fuel to the carburetor, means for regulably supplying air to the carburetor, motors for individually effecting regulation of said means, a common means for energizing said motors, and means for regulating energization of the motor which regulates the fuel supply.
